UNITED STATES PATENT OFFICE

2,620,411

DOOR HINGE OPERATED SWITCH

John W. Liley, Ferndale, Mich., assignor of fifty-five per cent to Michael J. Basso, Detroit, Mich.

Application October 15, 1949, Serial No. 121,625

2 Claims. (Cl. 200—54)

1

This invention relates to electric house lighting devices and has particular reference to a utility light and electric circuits for the same.

An object of the invention is to provide a utility light and circuits which are constructed and arranged so that the light may be automatically turned on and off by the opening and closing of a door, yet may be manually turned on and off at the light when the door is either open or closed.

Another object of the invention is to generally improve devices of the character indicated and to provide a device of such character which is economical to manufacture, simple in construction, and efficient in operation.

The foregoing and other objects and advantages of the invention will become more apparent as the description proceeds, reference being made from time to time to the accompanying drawing forming part of the within disclosure, in which drawing:

Fig. 1 is a fragmentary perspective view of the inside of a room showing a wall and a door on which are mounted the device embodying the invention.

Fig. 2 is an enlarged view of the device embodying the invention with parts broken away and parts in section to illustrate the construction and arrangement of other parts.

Fig. 3 is a view taken substantially on the line 3—3 of Fig. 2.

Referring now more particularly to the drawing, it will be understood that in the embodiment herein disclosed, the reference character 7 indicates a wall, the reference character 8 indicates the frame of a door, and the reference character 9 indicates the door on which are mounted the device embodying the invention. The invention resides in the construction, combination, and arrangement of elements. To carry out the invention, I provide a lamp base 10 which may be mounted in any position on the wall 7 by means of the perforated flange 10A. The base 10 supports a light socket 11, in which is a conventional light bulb 12, and which is electrically connected to the other elements of the device as hereinafter described. The base 10 also supports a two-way switch 13, which is manually controlled by means of a switch lever 14.

An automatic switch housing 15 is secured to the hinge of the door by means of a bracket 16, which has an outwardly directed ear 17, which is perforated to engage the pintle 18 of the hinge 18A. Mounted within the housing 15 is an auto-

2

matic plunger type switch 19 having a plunger 20, which is adapted to be contacted by the door frame 8 when the door 9 is in closed position. When the door 9 is closed, the plunger 20 is moved inwardly and opens the circuit through the automatic switch 19. The automatic switch 19, the housing 15, and its supporting elements are more particularly described and claimed in my co-pending application Serial No. 101,712, filed June 28, 1949, to which reference is made for greater certainty.

The light socket 11, the two-way switch 13, and the automatic switch 19 are electrically connected as hereinafter described. Electrical energy is provided for the device through a plug 21, which is arranged to engage the socket of a conventional outlet 22. Connected to the plug 21 are the wires 23 and 24, the wire 23 being connected to the terminal 30 of the automatic switch 19, and the wire 24 being connected to a wire 25, which in turn is connected, as at 26, to one of the wires 27 directly connected to the light socket 11. The other side of the light socket 11 is connected by means of a wire 28 to the terminal 29 of the two-way switch 13. Also connected to the automatic switch terminal 30 is a wire 31, which also connects directly to the terminal 32 of the two-way switch 13. The wire 33 connects at one end to the terminal 34 of the automatic switch 19 and connects at the other end to the terminal 35 of the two-way switch 13.

In operation when the door 9 is closed, the plunger 20 of the automatic switch 19 bears against the door frame holding the plunger 20 inwardly and holding the automatic switch open. In such position the light 12 would not burn. Inasmuch, however, as the plug 21 and the light socket 11 are also connected to the terminals 32 and 29 of the two-way switch 13 by means of the wires 25, 27, 28, and 31, the light 12 may be turned on and off manually when the door 9 is closed. It is also possible to manually control the light 12 when the automatic switch 19 is closed and the door 9 is open. This is possible because the terminal 34 of the automatic switch 19 is connected by the wire 33 to another terminal 35 of the two-way switch 13.

Having described my invention what I claim and desire to secure by Letters Patent is:

1. An article of manufacture comprising a cylindrical non-conductive housing, said housing having a flat side arranged to accommodate a mounting bracket, a mounting bracket secured to the flat side of said housing and having an outwardly directed perforated ear arranged to

engage the pintle of a hinge, an aperture in the flat side of said housing and a plunger-type switch secured to the flat side of said housing and having its plunger extending through the aperture in said flat side.

2. A switch assembly for mounting on a door hinge, comprising a hollow housing of electrically non-conductive material, said housing having a flat area arranged to engage a mounting bracket, a mounting bracket having a flat area overlying a portion of the flat area of said housing and having parallel sides arranged to engage opposite sides of said housing, an outwardly directed ear on said bracket having an opening therein arranged to accommodate the pintle of a door hinge whereby said bracket is secured to the hinge, an opening in the flat area of said housing and a

plunger type switch secured in said opening and having its plunger extending therethrough and in spaced parallel relation with the ear of said bracket.
